HOLLON RAWNSLEY, OF SPRINGVALE, MAINE, ASSIGNOR TO GOODALL WORSTED COMPANY, OF SANFORD, MAINE, A CORPORATION OF MAINE.

COUNTING-MACHINE.

1,209,203.

Specification of Letters Patent. Patented Dec. 19, 1916.

Application filed January 27, 1916. Serial No. 74,693.

To all whom it may concern:

Be it known that I, HOLLON RAWNSLEY, a citizen of the United States, and resident of Springvale, township of Sanford, Maine, 5 have invented an Improvement in Counting-Machines, of which the following description, in connection with the accompanying drawing, is a specification, like characters on the drawing representing like parts.

10 This invention relates to counting machines and has particular reference to such machines as are employed for counting bobbins or similar articles used in the manufacture of textile goods. This device functions equally for unfilled as for filled bobbins. The disadvantage of the machine at present employed is that a plurality of articles often pass the counter or registering device with the result that a single unit is 15 registered. A counting machine of this type is generally employed in conjunction with the usual sorting table and conditioning apparatus. When so used the counting device is interposed between the sorting table and 20 the conditioner so that the bobbins may be counted as they pass from the sorting table to the conditioning machine.

The object of this invention is to produce an improved counting machine which will 25 accurately count a plurality of articles presented thereto.

Another object is to provide such a counting machine with a wide range of adjustability to accommodate articles of variant 30 sizes and shapes.

Other objects of the invention will more fully appear from the following description and the accompanying drawings and will be pointed out in the annexed claims.

40 In the drawings, Figure 1 is a section through the counting machine; Fig. 2 is a side elevation of the same; Fig. 3 is a partial section on the line 3-3, Fig. 1; Fig. 4 is a side elevation of the drive for the endless belt or conveyer; Fig. 5 is a detail view of 45 the block raising cross-head.

In this selected embodiment of the invention the structure is shown as adapted to count various kinds of either filled or unfilled bobbins used in the textile art but, 50 obviously, with slight modification articles of other shapes and sizes may be counted. The sorting table 1, upon which are placed the bobbins 2, has associated therewith a

conveyer which functions to deliver the bobs- 55 bins to the registering or counting mechanism. In this embodiment, there is provided for this function, an endless belt 3 which travels between the two flat pulleys 4 and 5 so that the top run of the belt is 60 substantially in the horizontal plane of the sorting table surface which is cut away to permit the facile positioning of the bobbins upon the conveyer. The pulley 4, suitably journaled in the frame 11, is an idler, while 65 the pulley 5, is driven from the cam shaft 6 journaled in brackets 12 on the main frame. For this purpose a gear 7 is mounted to intermesh with the gear 8 with which the pulley 5 is revoluble and with the pinion 70 9 revoluble with the cam shaft 6. The pulley 5 is journaled in blocks, see Fig. 2, to allow for belt adjustment and hence the gear 7 is mounted in the adjustable plate 10 secured to the main frame 11 in order to permit of its movement to compensate for adjustment of the pulley 5 and its gear 8. The cam shaft is driven from a suitable power source. In this embodiment the transmission of the power from the source employed 75 is through the belting 13 which actuates the chain 14 through the intermediary of a clutch member not now claimed. This chain engages the teeth of a sprocket 15 mounted upon the cam shaft 6 which is revoluble therewith. 80

The sorting table has, as is usual, a relatively high backboard to permit a large number of bobbins to be piled thereon, while the side of the sorting table adjacent the 90 conveyer has, as shown in Fig. 3, a side rail 16. The longitudinal plate 17 is secured to the inside face of the rail 16. The function of this construction is to afford a guide on this side for the ends of the bobbins and 95 to reduce friction and, to assure durability, such plate is preferably metallic. The opposite ends of the bobbins 2 are directed in their travel with the conveyer by the guide 18 which similarly is preferably metallic in 100 substance. This guide 18 is, in this selected embodiment, so mounted as to be readily adjustable to accommodate varying lengths of bobbins or other articles. The guide has a preferably integral arm 19 which is de- 105 mountably secured to the outstanding arm 20 of an angle-iron by the bolt 22, the other arm 21 of which is demountably secured

by the bolt 67 to the cross bar 23 of the frame 11. A plurality of holes are provided in this bar 23 but for convenience only one is shown in Fig. 3. When bobbins or other articles of greater length than those illustrated are counted, the arm 21 is moved and bolted so as to give the desired width between the side rail plate and the guide 18 or it may be wholly removed in which case the guide 24 permanently secured to the frame performs its function. The bobbins 2 are thus carried along by the conveyer and guided to the mechanism which co-operatively functions to receive a single bobbin 15 at a time, to raise it and to cause the bobbin to be forced against a tripping mechanism which actuates a counting or registering apparatus and then is permitted to drop away from the machine.

20 The stop 25 and the upper face of the reciprocating block 26 in conjunction with the frame of the machine form substantially a receiving chamber to accommodate a single bobbin. The block 26, in descending to its 25 lowest position of vertical travel permits a bobbin to be delivered on the upper face thereof by the conveyer. The block 26 is normally held in its highest limit of travel by spring tensioned means and is depressed 30 to its lowest position by cam-actuated means. The block 26, in this selected embodiment, has a pair of reciprocally mounted stems 27 which bear at their lower ends a structure functioning substantially as a cross-head. 35 The transverse bar 28 of the frame of the machine has secured thereto, by any suitable means, a transverse member 29, preferably a casting. The two bosses 30 depend therefrom. The transverse member 29 and 40 the bosses 30 are bored or suitably apertured to admit the facile passage therethrough of the stems 27 of the block 26, each stem being thus reciprocal in a boss 30. The upper face of the member 29 is beveled to prevent the 45 accumulation of waste or dirt thereon. Such accumulation would seriously impair the camming function of block as such waste, firmly packed by repeated descents of the block, would not permit the full travel of 50 the block. This beveled face permits the sliding off of dirt or waste falling thereon from the bobbin conveyer or elsewhere. The lower ends of the stems are secured to the cross-head 31 by the nuts 32. The curved 55 arms 33 depend from the cross-head 31 adjacent its ends and are linked at their lower ends each to a spring 34. The cross-head and, hence, the stemmed block 26 are normally held in their elevated positions. The 60 cross-head is depressed against this spring tension through the intermediary of a cam and follower. A suitably shaped cam 35 is secured to and is rotatable with the cam shaft 6 and operatively engages the inner end of 65 the follower 36 pivotally mounted in a

bracket 37 on the frame of the machine. The outer end of the follower 36 bears upon the upper face of the head 38 carried on a screw received in threaded engagement in the cross-head. The head 38 preferably has recesses 70 39 to receive a pin or similar instrumentality to turn the screw on the cross-head in order to elevate or depress the head and thus adjustably alter the throw of the cross-head.

In Fig. 1 the block is shown in its highest 75 position of travel. At this point the ram 40, which is cam-actuated in timed relation to the block, forces the bobbin 2 against the trip 41 of the registering mechanism. The pivotally mounted trip swinging outward 80 permits the bobbin to roll down the chute 42 to a conditioning machine or to a suitable receptacle. The ram 40 extends the width of the conveyer and is suitably slidably mounted in the frame sides. It is directly 85 actuated by means secured to the ears 43 between which is pivotally secured the rod 44 and this rod has mounted thereon suitable tension means such as the coil spring 45, the lower end of which bears against the 90 collar 46 while the upper end bears against the sleeve 47 which is slipped upon the rod and held against demounting by the nuts 48. The spring 45 is preferably sufficiently stiff so that, normally, relative movement is not 95 permitted between the sleeve 47 and the rod. The spring means is here interposed as a single factor of safety to guard against injuring the ram or bobbin should either become jammed. The arm 49 is pivotally secured to the sleeve 47 and, at its other end, is secured to the rock shaft 50. This shaft is pivotally mounted, as shown in Fig. 3, in the machine frame. The follower 51 is fastened and imparts motion to the rock shaft. 100 The lower end portion of this follower is held against the eccentric cam 52 of the cam shaft by the spring 53, one end thereof being attached to the follower and the other to the frame by the pin 54. The ram 40 105 thus reciprocates in obedience to the movement of the eccentric cam 52 secured to the cam shaft 6 in a definite cam-function relation to the cam 35 which controls the movement of the elevating block 26. The transverse bar 55 extends across the machine and forms the top of the bobbin receiving chamber. This member is preferably made in two pieces in order to permit full forward movement of the ears 43 of the ram 40. The 110 guide 56 is positioned above the conveyer and adjacent the end portion thereof and functions to prevent the bobbins from piling and serves to retain them in alignment adjacent the receiving chamber. This guide 56 115 is suspended in such manner that it may be adjusted to bobbins of different thicknesses. In this embodiment a boss 57 is preferably integrally formed on the guide. This boss 57 terminates in a threaded stem 58 which 120

is held in relatively adjustable position by the nuts 59 to a block which in turn is secured to the bar 23 of the frame 11.

Any suitable form of registering mechanism may be used and in this embodiment it consists of the trip 41 which, through a system of levers functions to actuate the register 60. The trip is pivotally mounted on the frame and secured to the shaft of the trip is the arm 61, (see Fig. 2) which has a plurality of holes 62, in one of which may be secured a pin carried by the arm 63 whereby the two arms are pivotally secured together. The upper end of this arm 63 is pivotally secured to the rod 64 which is rigidly mounted in the block 65 secured to the machine frame. The block 65 is adjustably pivotally mounted in the machine frame to afford adjustment of the rod 64, correlating the movement of its pivot to any change in adjustment of the rod 63. This transverse rod 64 is in turn secured to an upright leading to the lever 65 of the register 60 which is supported by the bracket 66 secured to the frame.

The operation of the device is simple, accurate and efficient and while various articles may be counted by this mechanism, this embodiment is particularly adapted to 30 count bobbins. The high back of the sorting table permits a relatively large number of bobbins to be placed thereon. The ends of the sorted bobbins are abutted against the longitudinal rail plate 17 which serves as a 35 bobbin positioning member. Thus positioned, they are manually fed upon the conveyor and thereby carried to the receiving chamber while coincidently directed on their other ends by the guide 18 the front 40 of which is flared as shown in Fig. 3, to admit readily the bobbins. From the conveyor the bobbins one at a time pass to the receiving chamber when the block 26 is in depressed position under the action of the 45 cam follower 36. Upon the elevation of the then spring-tensioned block, the bobbin is raised while retained by the sides of the frame and the back stop 25. The shape of the cam 35 permits of a definite amount of 50 lost motion when the block is at its highest point of travel. At that time, the ram 40 indirectly actuated by the eccentric cam 52 moves forward. The relative positions of the various parts of the counting machine 55 at such time is shown in Fig. 1. The ram 40, moving forward, pushes the bobbin against the pivoted trip 41 which, in swinging backward, causes a unit to be registered on the register dial and also permits the 60 bobbin to drop down the chute 42 to a conditioning machine or a suitable receptacle. By the interposition of coiled springs in the actuating means for the ram 40 and for the block 25 liability to derangement of or of injury to the machine and to the articles being

counted is minimized. Should an article become jammed in the receiving chamber, the maximum force exerted against the article by the block 26 is only that of the springs 34, the cam follower 36 functioning idly as 70 its true working path is in a downward direction against the tension of these springs. Similarly, the maximum force exertable by the ram on a jammed article is limited to that of the spring 45 in tensioned forward 75 position, as the sleeve 47 riding down the rod 44 cannot move the ram 40 against resistance greater than that of the spring 45 in such forward coiled position. The guide 18 is provided with an adjustable mounting 80 so that when longer bobbins or articles are counted, the guide may be moved to the left of the position shown in Fig. 3 or, it may, if necessary, be removed altogether. In the latter contingency, the rail 24 functions as 85 the left guide. The overhead guide 56 is provided with an adjustable mounting whereby its position may be vertically altered. The adjustment is employed when the articles are of greater thickness than 90 those disclosed in the drawings herein. This guide is raised or lowered through manipulation of the nut 59 on the threaded stem 58. The path of traverse of the ram 40 may be regulated by the plurality of adjustments 95 on the ram arm and its connections.

There is thus provided a simple and efficient counting machine which accurately registers the passage of each and every article therethrough and which has a wide 100 range of adjustability to accommodate varying sizes of articles. Its construction cost is relatively low and the structure is durable, not liable to derangement or to injure the articles counted. Its operative efficiency 105 may be maintained at a higher rate of speed than the present types.

Having thus described my invention, what I claim as new and desire to secure by Letters Patent, is:

1. In a counting machine, a counting instrumentality, reciprocating means to present articles to the counting instrumentality, and means reciprocating in timed relation to said first-mentioned reciprocating means and actuated independently thereof to cause said presented articles to actuate the counting instrumentality.
2. In a counting machine, a counting instrumentality, yieldably actuated means for presenting the articles to said instrumentality and means for causing the articles to operate the counting instrumentality.
3. In a counting machine, a counting instrumentality, a reciprocating block to present articles to the counting instrumentality and means operated independently of the block for causing the presented article to actuate the counting instrumentality.
4. In a counting machine, a counting in-

strumentality, a yieldably actuated block to present articles to the counting instrumentality and means operated independently of the block for causing the presented article to actuate the counting instrumentality.

5. In a counting machine, a counting instrumentality, a movable block, a movable ram, coördinated means yieldably operable from a single shaft to actuate the block and 10 the ram, and thereby cause articles to be presented to and to actuate the counting instrumentality.

6. In a counting machine, a counting instrumentality, a member movable to present an article to said instrumentality, supporting means for said member normally tensionally held in elevated position, a head on said supporting means, an element engaging said head to depress the same and to 20 permit its return to normal position, means for adjusting said head on said supporting means whereby its travel may be altered, and means movable to cause said presented article to actuate the counting instrumentality.

25 7. In a counting machine a counting instrumentality, means for successively presenting articles adjacent the instrumentality, a guiding member on each side of said presenting means, a complementary removable guide to coöperate with one of said members, said complementary guide being adjustable coöperatively to guide different-sized articles and removable to permit guiding of largest articles, and means to cause the presented articles to actuate the counting instrumentality.

8. In a counting machine, a counting instrumentality, a conveyer for the articles to 40 be counted, means successively to present the conveyed articles to the counting instrumentality, a ram, means for slidably mount-

ing said ram, means for reciprocally actuating said slidable ram in timed relation to said presenting means whereby the ram 45 causes said presented articles to actuate the counting instrumentality.

9. In a counting machine, a counting instrumentality, a member tensionably held in elevated position, means for depressing said 50 member against tension to receive an article and thereafter permitting return to elevated position whereby said article is presented adjacent the instrumentality, and means movable to cause said article to actuate the 55 instrumentality and be thereby counted.

10. In a counting machine, a counting device, a conveyer for advancing articles successively, means to present the foremost article adjacent said device, means movable to 60 cause the presented article to operate the counting device, a driven member, means on said member continuously to drive the conveyer and to drive, in timed relation, the presenting means and the said movable 65 means whereby articles are successively advanced, presented to and counted by the counting device.

11. In a counting machine, a counting instrumentality, means for advancing articles 70 successively, means to present the foremost article adjacent said instrumentality, means movable to cause the presented article to operate the instrumentality, a driven member, a cam thereon, a follower to actuate said 75 presenting means and a follower to actuate said movable means, said cam being shaped to actuate the followers in timed relation whereby the articles are successively presented to and counted by the instrumentality.

In testimony whereof, I have signed my name to this specification.

HOLLON RAWNSLEY.
